Primary Examiner — Mitchell Siegel*(74) Attorney, Agent, or Firm* — Stoel Rives LLP(57) **CLAIM**

The ornamental design for a water slide, as shown and described.

DESCRIPTION

FIG. 1 is a top left isometric view of a waterslide showing the new design;

FIG. 2 is a front side elevation view thereof;

FIG. 3 is a rear side elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines showing in FIGS. 1-7 are for illustrative purposes only and form no part of the claimed design. The dotted lines in FIGS. 1-6 are illustrative of water spray patterns.

1 Claim, 6 Drawing Sheets(56)
